CLAIM

The ornamental design for an interchangeable lens for camera, as shown and described.

DESCRIPTION

The patent or application file contains at least one drawing executed in color. Copies of this patent or patent application publication with color drawing(s) will be provided by the Office upon request and payment of the necessary fee.

FIG. 1 is a Front view of an interchangeable lens for camera showing my new design;

FIG. 2 is a Back view thereof;

FIG. 3 is a Top view thereof;

FIG. 4 is a Bottom view thereof;

FIG. 5 is a Left view thereof;

FIG. 6 is a Right view thereof; and,

FIG. 7 is a Perspective view thereof.

The broken lines show portions of the interchangeable lens for camera that form no part of the claimed design.
